STEEL HOUSE

Harry Scullin, St. Louis, Mo., assignor to Scullin
Steel Co., St. Louis, Mo., a corporation of
Delaware

Application April 24, 1931, Serial No. 532,541

6 Claims. (Cl. 189—1)

This invention relates, broadly speaking, to the use of steel as a material for building construction and more particularly is concerned with the provision of an improved, simplified and more durable steel frame for houses.

The use of steel in building houses and residences is a comparatively recent development, and the accomplishments that have so far taken place in this field have been, at least in comparison with the present invention, complex, expensive and abortive. For instance, steel in great quantities has been used in putting up the comparatively simple framework of a residence with the attendant undesirable factors of high cost of materials and inconvenience of construction. Another disadvantage which has customarily accompanied the prior efforts has been the use of separate or removable fastenings to secure together the steel frame members. Such members are troublesome to put in place and are apt to become loose during wear. A still further disadvantage of the prior attempts has resided in the necessity of specially forming the structural members. This latter requirement increases the cost and renders it necessary to have the members specially rolled and shaped in the mill.

With the foregoing desideratum in view the present invention is directed to the provision of an improved type of structure that eliminates the objections and disadvantages of the prior structures and retains the desirable features of the steel frame construction. Numerous features of the invention will appear from a reading of the specification appended hereto, in the light of the accompanying drawings, but for introductory purposes a few of the many desirable attributes of the invention will be specifically set forth.

In the first place the invention contemplates the elimination of separate fastenings and the substantial strengthening of the structure through the provision of an integral and all-steel framework. Then again in order to conserve material the invention contemplates constructing the house or residence frame in multiples of small units. This analytical method of construction is to be contrasted with the haphazard methods now in vogue of placing steel indiscriminately at points where it appears necessary.

The invention eliminates the necessity of providing specially formed frame members and contemplates the use of standard steel sections throughout. As disclosed herein the sections are mainly channel bars or I-beams which afford guide ways for the reception of building or insulating blocks. Many other features of construc-

tion are included in the invented assemblage and comprise, for example, a novel ridge pole construction, an improved manner of building the eaves, a new design of floor level insulators, and an improved method of applying roofing material to the frame.

As hereinbefore pointed out, other objects and features of the invention will become apparent from a reading of the following specification in the light of the accompanying drawings, in which

Figure 1 is a view in perspective of a steel frame for a house constructed in conformity with the present invention.

Figure 2 is a detail perspective showing the connection of the vertical beams to the foundation member.

Figure 3 is a detail view in section showing the manner of insulating the floors of the house.

Figures 4 and 5 are views showing the manner of inserting insulating material forming the walls of the house.

Figures 6 and 7 display the application of lathes and plaster to the walls.

Figures 8 and 9 show the manner of holding the roofing material in place, and

Figure 10 is a modified form of roof structure.

For the sake of convenience the structure illustrated in the drawings will be described by starting with the basement or bottom portion and proceeding upwardly to the ridge pole or top of the house. Accordingly the reference numeral 10 indicates a concrete basement or foundation of the type generally employed in houses today. Vertically placed within the basement are supporting columns 12 for carrying horizontally extending supporting beams 14, the top of the beams 14 being approximately on the level with the top of the foundation 10. It will be understood and appreciated that if desired the foundation 10 may be of less height, located beneath the earth line, and the vertical supporting beams may be of correspondingly greater length. In this event the foundation will not show from the outside and the entire walls may then be a matter of selection, such as brick, cement block, etc.

Extending completely around the foundation is a hollow structure member or box 16 which is shown more clearly in Figure 3. This box forms the base of the frame and is secured to the foundation by means of bolts 18 which pass through the box and base plates 20 and with bolts 19 are buried in the foundation 10. The box-like member 16 may be formed in any desired manner, as, for example, by welding together the edges of the flanges of oppositely facing channel beams. The

member 16 serves as an excellent insulator for the house and prevents dampness and moisture from passing from the surrounding earth up into the walls of the dwelling, and to this end the member 5 16 may, if desired, be packed, as shown in Figure 3, with an insulating material.

Welded to the inner side edge of the member 16 is an angle bar or other suitable laterally projecting flange 22 for supporting floor beams 24, 10 which terminate slightly short of the box members 16, leaving a small expansion area 21. The beams 24 span the foundation and can conveniently be dropped into place upon the flanges 22, 15 properly adjusted with respect thereto, and finally may be welded to contribute to the integral frame structure. Preferably, the floor beams 24 rest upon the horizontally extending supporting beams 14 and thereby receive support at their central portions.

20 The sub-floor, as illustrated in Figure 3, is of an exceedingly durable yet flexible construction comprising a corrugated metal base 23 filled with mastic cement filler and bond 25 and covered with a composition tile flooring 27 or other suitable material. This construction of the sub-floors 25 provides a more resilient base than the present construction employed in steel buildings, and also affords a better bond for the materials placed upon it.

30 In order to provide an exceedingly strong and durable framework with the least amount of material, the floor beams 24 are spaced uniformly from one another in accordance with some unit of measurement, as, for example, 24 inches, 30 35 inches, 36 inches, etc. This unit is determined by computation, taking into account the various loads that are to be imposed, the size of the house and other pertinent factors. When once the unit has been adopted it becomes standardized in the 40 dwelling and all of the other parts of the frame are placed in conformity therewith.

Extending upwardly from the insulating member 16 are vertical wall beams 26. These beams 45 form the peripheral boundary of the frame and are spaced apart according to the unit of measurement adopted in the floor construction. Furthermore, in order to increase the rigidity of the structure the vertical wall beams 26 extend upwardly from the points of junction of the floor beams 24 and the insulating member 16. Thus 50 if the reader will pause to trace one of the horizontal floor beams he will find that at its opposite ends there is a vertically extending wall beam leading therefrom.

55 The floor beams 24 as well as the vertical wall beams 26, and in fact the remaining structure members of the frame, are all standard steel sections. That is, they are I beams or channel beams 60 or flange beams of some sort of standard dimensions and of the type customarily known in the trade as "standard sections". It has been impossible to illustrate this clearly in the perspective views shown in Figures 1 and 2 of the drawings, but nevertheless the use of standard sections 65 throughout is an exceedingly important aspect of the invention and is illustrated in the drawings wherever occasion permits.

70 The reference numeral 28 is used to indicate horizontal members disposed in the vertical side walls. These members 28 are inserted only at those points where it is desired to form window or door openings, and therefore, they serve the dual function of marking the openings and reinforcing in a horizontal direction the vertical 75 extending frame members.

The vertically extending beams 26 are practically all in the outer wall of the frame and if attention is devoted to the few vertical beams arranged elsewhere in the structure, it will be observed that there are only a very few vertically extending supporting beams 30 disposed within the interior of the house. These beams 30 contribute to the support of the floors above and may be used to mark wall boundaries. They are scarce enough, however, that they form no part of the partition walls marking off the different rooms and therefore the partition walls do not carry any substantial weight. This permits the partition walls to be knocked down with ease and rearranged to change the location and shape of the rooms on the different floors and thereby affords another important feature of the invention. Therefore, to repeat, each floor of the house within the outer walls is substantially 80 unobstructed by frame members; this being an important aspect of the invention not afforded by prior structures.

At the beginning of the second story another insulating box-like member 32 marks the second floor level and performs much the same function 100 as the lower insulating member 16. Beams 34 extend across the second floor and afford ceiling beams for the rooms beneath and flooring beams for the rooms above. These beams 34, it will be observed, extend from the points of junction of 105 the vertical wall beams 26 with the insulating member 32 and lie above and parallel to the lower flooring beams 24. This disposal of the beams 34 carries forward the idea of building in units to conserve material and to afford greater rigidity 110 and durability.

The eaves of the house are formed by sloping or diagonally extending beams or sections 36 which are welded at two points to the horizontal insulating member 32, and the vertically extending 115 wall beams 38 of the second floor, or the sloping roofing beams 40. At their lower extremities the eave beams 36 carry an inwardly extending shelf 42 and drains 44.

The second floor is constructed very similarly 120 to the lower floor and is provided with similar horizontal and vertical beam members serving the same purpose as the corresponding members in the lower story.

The roofing members, likewise formed of standard sections, are welded to the vertically extending wall members of the upper stories and have converging extremities 46, 48 between which extremities is inserted a ridge pole 50, in the form of a ribbon of steel of standard shape. The roofing beams, it will be observed, are also spaced apart to carry out the multiple unit idea and in this manner serve to complete an exceedingly rigid structure assured of a long life. It will now be observed that carrying out of the unit theory 130 results in a construction comprising a plurality of vertical sections joined together at numerous points by horizontally extending members. A typical section in the house, as illustrated, comprises a horizontal flooring beam 24, the upwardly extending wall beams leading from opposite ends of the flooring beam, the ceiling beams leading from the upper extremities of the vertical wall beams and the converging roofing beams which extend upwardly from the ceiling beams. 135 All of these beams lie within the same plane and the number of planes in the house frame coincides with the selected number of multiples of the unit chosen.

140 Gables are conveniently formed as indicated 150

by the reference numeral 52 and comprise vertical wall beams 54, horizontal flooring beams 56 and converging roofing members 58.

The structural members are all welded together to form what amounts to a unitary frame and the reader may be assured that forming the frame in this manner affords a structure that is rigid beyond belief and that conserves steel to the utmost.

10 Turning for a moment to further details of construction, Figures 4 and 5 show the contemplated manner of inserting insulating blocks 60 between adjacent vertical wall beams 26, utilizing the channels 62 of the beams as guideways for receiving the outer edges of the insulating material.

Figures 6 and 7 show reinforced expanded metal lathes 64 spot-welded to the vertical beams on the exterior walls for receiving and retaining 20 stucco, plastic cement, etc. 66. Likewise, the reinforced expanded metal lathe is spot-welded to the lowermost flanges of the ceiling beams 24 to provide a base or foundation for ceilings.

It is contemplated forming the roof of insulating blocks to retard the penetration of heat and cold and Figures 8 to 10 inclusive show different ways of accomplishing this desired end. In Figure 8 the roofing beams 46 are composed of channel beams having flanges extending in

30 the same direction and insulating blocks 68 are inserted within the channel of one of the beams and against the base of the other. To hold the blocks in this inserted position retaining bars or clips 70 are spot-welded in place beneath the blocks.

35 On the other hand, as shown in Figure 10, an alternate form of construction consists in spot-welding T-bars 72 to the roofing beams 46 and employing in connection therewith anchor clips or straps 74 for holding the insulating roof 40 blocks 68. At the peak, above the ridge pole or ribbon plate 50, angle bars 76 are employed in place of T-bars that are used at points lower down and the angle bars co-operate with anchor clips or straps 78 in securing the upper ends of 45 the top-most insulating blocks and the roof peak piece 80. With the type of construction shown in Figure 10 the number of roof rafters may be reduced without weakening the structure. After 50 the insulating blocks have been placed in position a thin sheeting or coat of waterproofing material 82 is applied and is then covered over with suitable material, as for example, asbestos shingles 84.

There are other features relating, for example, to the nesting of the stairs in the structure, such stairs being metal; and the combining of a clothes shute framework 86 within the turn of the stairs, and utilizing the shute frame as a vertical supporting member; all of which 60 features are important and which contribute to the efficiency of the structure.

All of the matters described unite in contributing to and affording a comparatively inexpensive all-steel, all-welded frame construction that is durable and rigid and exceedingly satisfactory.

Having thus described my invention what I claim as new and desire to secure by Letters Patent of the United States is:

70 1. A steel frame for houses comprising in combination, a foundation, a box-like frame supported on and extending the length of the foundation on all sides thereof, means securing said frame

to said foundation, said frame being hollow and providing a receptacle for insulating material to thereby insulate said frame, vertical wall beams supported on said box-like frame, and horizontal beams also carried by said frame and rigidly connecting therewith. 80

2. A steel frame for houses comprising in combination, a foundation, a hollow frame formed by welding together the flanges of adjacent channel beams positioned on said foundation and secured thereto, said frame providing a receptacle for insulating material to thereby insulate said frame, vertical beams supported on said frame and suitably welded thereto, and horizontal beams marking each floor of the building, said vertical and horizontal beams being standard I-shaped structural members. 85

3. A steel frame for houses comprising, in combination, a foundation, a hollow structural member of substantially rectangular cross section supported on and extending the length of the foundation on all sides thereof, vertical beams supported on and welded to said hollow member, horizontal beams providing horizontal floors in the building, a flange extending laterally from one side of said hollow member, and the horizontal beams forming the first floor of the building being disposed upon and carried by said laterally extending flange. 95

4. A steel frame for houses, in combination with a foundation, a hollow structural member positioned on said foundation and secured thereto, vertical beams supported on and welded to said hollow member, a second structural member supported on said vertical beams and being welded to the ends thereof, horizontal beams marking each floor of the building and rigidly connecting with said structural members, respectively, a corrugated metal plate providing a subflooring welded to said horizontal beams, and flooring supported by said corrugated plate. 105

5. A steel frame for houses, in combination with a foundation, a hollow structural member of substantially rectangular cross section positioned on said foundation and secured thereto, vertical beams supported on said hollow member, insulating material located between said vertical beams and supported thereby, said material extending the height of the beams to provide insulated vertical walls, horizontal beams marking each floor of the building and disposed in alignment with said vertical beams, a corrugated surfacing covering said horizontal beams, and a flooring supported by said corrugated surfacing. 120

6. A steel frame for houses, in combination with a foundation, a hollow structural member of substantially rectangular cross section supported on and extending the length of the foundation on all sides thereof, vertical beams supported on and welded to said hollow member, horizontal beams carried by said hollow member and rigidly joined thereto, said horizontal beams providing the first floor of the building, a second hollow member supported on and welded to the ends of the vertical beams, other horizontal beams carried by said second hollow member and rigidly joined thereto forming the second floor of said building, said horizontal beams and vertical beams being disposed in vertical alignment. 135

HARRY SCULLIN.
